(57) **CLAIM**

The ornamental design for a core for food products mold, as shown and described.

DESCRIPTION

FIG. 1 is a perspective view of a core for food products mold showing my new design;

FIG. 2 is a front view thereof;

FIG. 3 is a rear view thereof;

FIG. 4 is a left view thereof, with no ornamentation claimed for the right side view;

FIG. 5 is a top view thereof; and,

FIG. 6 is a bottom view thereof.

In the drawings, the broken lines depict portions of the article that form no part of the claimed design.
